UNITED STATES PATENT OFFICE.

ARTHUR WILLIAM GOTHLBERG, OF NEWARK, NEW JERSEY.

CABLE SUPPORT.

Application filed December 22, 1925. Serial No. 76,950.

This invention relates to cable supports, and more particularly to such supports for electric cables or conductors connected with and suspended by a plurality of articulated 5 insulators.

It is the particular object and purpose of my present improvements to provide such a supporting means for cables or conductors in the form of a clamping device, which 10 under normal conditions has tight clamping engagement upon the cable to prevent shifting of the latter but which is so constructed, that in the event that the tension upon the cable on opposite sides of the device becomes 15 unbalanced so as to cause the insulator string to swing from its normal perpendicular position, the clamping pressure upon the cable will be automatically released, thus permitting the cable to slip until the tension is 20 again equalized when the clamping or holding pressure of the supporting device upon the cable will be resumed.

It is a further general object of the invention to provide a cable supporting device 25 of the above character consisting of few parts of simple form and rugged construction so that the device is not liable to get out of order and can be produced at nominal manufacturing cost.

With the above and other objects in view, the invention consists in the improved cable support, and in the form, construction and relative arrangement of its several parts as will be hereinafter more fully described, 35 illustrated in the accompanying drawings and subsequently incorporated in the subjoined claims.

In the drawings, wherein I have illustrated one simple and practical embodiment 40 of my improvements, and in which similar reference characters designate corresponding parts throughout the several views,—

Figure 1 is a side elevation showing my improved cable support as used in connection 45 with an insulator string, and illustrating the insulator string in dotted lines swung in one direction from its normal position by excessive tension on the cable on one side of the support;

Fig. 2 is an enlarged side elevation of the supporting device, and

Fig. 3 is a sectional view taken substantially on the line 3—3 of Fig. 2.

Referring in detail to the drawings, for 55 purposes of illustration, I have shown a string of insulators 5 which may be of any

approved form and construction and articulated with each other by any desired means usually employed for this purpose. This string of insulators at its upper end is pivotally suspended as at 6 from an arm of the 60 tower or other structure shown at 7.

With the lower insulator 5 the upper end of a yoke 8 is pivotally connected as at 9. The arms of this yoke are provided at their 65 lower ends with apertured hubs 10 to receive the bolt 11. This bolt is also engaged through an opening 13 in a boss formed on the lower central portion of the clamping member 12. Suitable nuts 14 threaded on 70 one end of the bolt 11 retain the parts in connected relation with the inner faces of the hubs 10 on the yoke arms bearing against the opposite sides of the member 12. The upper surface of this clamping member is 75 provided centrally thereof with the longitudinally extending groove 15. A complementary clamping member 16 is provided with a similar groove 17, and these grooves of the clamping members are adapted to receive the 80 lower and upper portions respectively of the cable indicated at 18.

Each clamping member is provided on opposite sides thereof and adjacent its ends with apertured lugs 19, said lugs receiving 85 bolts 20 having suitable heads on their upper ends and provided with coil springs 21 bearing at their upper ends against the lugs 19 on the clamping member 12 and engaged at their lower ends with the washer plates 22 90 which are adjustable upon each of the bolts by means of the nuts 23 whereby the tension of said springs can be regulated as desired. Through the medium of these springs, it will be understood that the two clamping members 12 and 16 are resiliently urged in relatively opposite directions so that under normal conditions the cable 18 is clampingly 95 confined in the grooves 15 and 17 of said members.

The upper clamping member 16 is additionally provided on each side thereof at its center with a lug 24 and these lugs are adapted to be engaged by cams 25 formed on the upper sides of the hubs 10 of the 105 yoke 8, each of said cams projecting in opposite directions from the hub center.

From the above description, the construction and operation of the device can be readily understood. While the tensional 110 stress of the cable 18 on opposite sides of the supporting device remains substantially

2

equal, the string of insulators 5 will maintain a substantially normal perpendicular position as shown in full lines in Fig. 1 of the drawings. When, however, tension upon the cable at one side of said device is greater than at the other side thereof, as by reason of a heavy coating of ice accumulating on the cable, or when the cable is struck by a tree limb or other object, the string of insulators will be swung in one or the other direction from such normal perpendicular position as indicated in dotted lines in Fig. 1 of the drawings. The yoke 8 will thereby be caused to swing or pivotally turn on the bolt 13, said yoke remaining substantially at all times in alignment with the axis of the insulator string. Thus, the cams 25 at one of their ends are caused to exert an upward bearing pressure on the lugs 24 of the upper clamping member and thus move the same upwardly relative to the lower member against the action of the springs 21. The clamping pressure on the cable 18 is thus automatically released so that said cable may readily slip through the clamping or holding device while said device can slide freely on the cable. In this manner, liability of the cable being broken when subjected to an abnormal and excessive tensile strain or pull will be obviated. As this strain is removed and the tension again equalized, the insulator string returns to its normal perpendicular position and the cams 25 move out of engagement with lugs 24 so that the clamping or holding pressure of the members 12 and 16 upon the cable 18 is resumed.

From the above, it will be seen that I have devised a support for electric cables or conductors which will positively hold or sustain the cable in proper position relative to the insulators under normal conditions, and yet will automatically release the cable in response to an excessive tensile strain thereon from either direction. The device as above described consists of relatively few elements of simple form and construction which will operate in a positive and reliable manner, and are not liable to get out of order. The illustrated example of my present improvements is believed to be entirely practical in every respect. Nevertheless, it is to be understood that the essential object and purpose of the device might also be attained in other alternative mechanical structures, and I accordingly, reserve the privilege of resorting to all such legitimate changes in the form, construction and relative arrangement of the several parts as may be fairly embodied within the spirit and scope of the invention as claimed.

I claim:

1. In combination with cable suspension means pivoted at its upper end for swinging movement, a cable support connected

with the lower end of said suspension means, said support including complementary parts to clampingly hold the cable against shifting movement relative to the suspension means under normal conditions, and means 70 for positively moving one of said parts relative to the other to release the cable when said suspension means is swung from its normal position by excessive tensile strain on the cable at one side thereof. 75

2. In combination with cable suspension means pivoted at its upper end for swinging movement, a cable support connected with the lower end of said suspension means, said support including complementary members 80 and means urging said members into clampingly engagement against opposite sides of the cable to hold the same against movement relative to the suspension means under normal conditions, and cam means automatically operable when the suspension means is swung in one direction by an excessive tensile strain on the cable at one side thereof to move said members relative to each other and release the cable. 90

3. In combination with cable suspension means pivoted at its upper end for swinging movement, a cable support connected with the lower end of said suspension means, said connecting means comprising a yoke 95 and the support including complementary members mounted in said yoke, means yieldingly connecting said members and urging them into clampingly engagement upon the cable to hold the latter against shifting movement relative to the suspension means under normal conditions, and one of said members and said yoke being provided with parts automatically coacting with each other when the suspension means is swung in one 100 direction by abnormal strain on the cable at one side thereof to thereby release the clamping pressure of said members on the cable. 105

4. In combination with cable suspension 110 means pivoted at its upper end for swinging movement, a cable support connected with the lower end of said suspension means, said connecting means comprising a yoke pivotally connected with the suspension 115 means and said support including complementary upper and lower cable clamping members and means yieldingly holding said members against relative movement in clamping engagement upon the cable, means pivotally connecting the arms of the yoke with the lower clamping member, said upper clamping member having lugs on opposite sides thereof, and cams on the yoke arms 120 automatically coacting with said lugs when the suspension means is swung in one direction by excessive tensile strain on the cable whereby the clamping members are relatively moved to release their clamping pressure on the cable. 125

5. Means for connecting an electric cable to a string of insulators, comprising relatively movable cable clamping members, means for pivotally suspending said members from the lower end of the insulator string, and means automatically acting when the insulator string is swung in one direction by an excessive tensional strain on the cable at one side of the connecting means, to separate said members relative to each other and release the cable.
6. Means for connecting an electric cable to a string of insulators including a suspending element adapted for connection to the insulator string, cable clamping means including a member movably supported by said element, means for retaining said member in clamping engagement upon the cable in the normal position of the insulator string to prevent movement of the cable relative thereto, and said member and the suspending element having parts automatically coacting when the insulator string is swung in one direction from its normal position by excessive tensional strain on the cable to positively move said member and release the cable, and said coacting parts, upon the return of the insulator string to its normal position permitting of the restoration of the clamping pressure of said member upon the cable.
7. Means for connecting an electric cable to a string of insulators comprising a suspension element adapted to be connected to the insulator string, cable clamping means including a member supported by said element for movement relative thereto, means yieldingly urging said member into clamping engagement upon the cable to hold the latter against movement relative to the insulator string in the normal position thereof, and means connected with said suspension element and coacting with a part on said member when the insulator string is swung in one direction by an excessive tensional strain on the cable to positively move said member relative to the suspension element and release the cable, and said means, upon the return of the insulator string to its normal position permitting of the restoration of the clamping pressure of said member upon the cable.
8. In combination with a suspended string of insulators, cable clamping means connected with the lower end of said insulator string including a movable clamping member, and means cooperating therewith to hold said member in clamping engagement upon the cable in the normal position of the insulator string but permitting angular movement of said member and release the clamping pressure on the cable upon displacement of the insulator string from normal perpendicular position by tension on the cable, and said means acting to move said member into engagement with the cable and restore the clamping pressure thereon upon the return of the insulator string to its normal position.
9. In combination with a suspended string of insulators, cable clamping means connected with the lower end of the insulator string including relatively movable clamping members, and means for automatically releasing a clamping pressure of said members on the cable when the insulator string is displaced from a normal perpendicular position by tension on the cable and restoring such clamping pressure upon the return of the insulator string to normal position, said means consisting of means acting to yieldingly resist relative angular movement of said members with respect to the cable, and additional means operable in the swinging movement of the insulator string to overcome said resisting means and effect such relative movement of the cable clamping members.
10. In combination with suspension means mounted for swinging movement, a support carried thereby, a clamp carried by the support, means for maintaining the clamp in clamping relation to a cable, and independent means, other than the cable connected with the support and cooperating with the clamp for rendering the maintaining means ineffective upon the occurrence of excessive longitudinal strain upon the conductor at one side of the suspension means.
11. In combination with suspension means mounted for swinging movement, a support, a clamp carried by the support, means normally maintaining the clamp in clamping engagement upon a conductor, and means carried by the support and connected with the clamp for rendering the maintaining means ineffective upon swinging movement of the suspension means beyond a predetermined extent.
12. In combination with a support mounted for swinging movement, conductor clamping means comprising relatively movable members carried by the support, means connecting said members and normally maintaining them in clamping relation to a cable, and means cooperating with the support and one of said members for rendering the clamping relation ineffective upon the occurrence of swinging movement of the support beyond a predetermined limit.
13. In combination, a swingably mounted support, relatively movable clamping members carried thereby, means normally urging said members together for maintaining a clamping action upon a cable, and means independent of said clamping action maintaining means and independent of the cable for rendering the clamping action ineffective upon swinging movement of the support beyond a predetermined extent.

- 4.
14. In combination with cable suspension means mounted for swinging movement, a cable support carried by said suspension means, relatively movable clamping members located within the confines of the support and one pivoted thereto at a point below the cable, means for maintaining said members in clamping relation to the cable, and means located within the confines of said support and at opposite sides of the clamping members for releasing the clamping action upon the occurrence of excessive longitudinal tension upon the cable at either side of the suspension means. 35
15. In combination with cable suspension means mounted for swinging movement, a support pivoted thereto, upper and lower cable clamping members located within said support, a pivotal mounting for connecting the lower clamping member with the support at a point below the cable, means normally maintaining said clamping members in clamping relation to the cable, and upwardly extending means mounted at said pivotal mounting and coacting with the upper clamping member for releasing the clamping engagement upon the occurrence of an excessive longitudinal strain upon the cable at one side of the support. 40
16. In combination with cable suspension means mounted for swinging movement, a cable support carried by said suspension means, relatively movable clamping members located within the confines of the support and one pivoted thereto at a point below the cable, means for maintaining said members in clamping relation to the cable, and means located within the confines of said support and at opposite sides of the clamping members for releasing the clamping action upon the occurrence of excessive longitudinal tension upon the cable at either side of the suspension means. 45
17. Means for connecting a conducting cable to a string of insulators, comprising a supporting clamp including coacting upper and lower members, means for maintaining the members in clamping relation to the cable and further including a support for the members pivotally connected with the lower one thereof at a point below the cable and adapted to be connected with the string of insulators, and means carried by the clamp acting below the upper member for effecting release of the clamping action upon swinging movement of the support as the result of excessive tensional strain applied to the cable at one side of the support. 50
18. In combination with cable suspension means mounted for swinging movement, a cable support carried by said suspension means, relatively movable clamping members located within the confines of the support and one pivoted thereto at a point below the cable, means for maintaining said members in clamping relation to the cable, and means located within the confines of said support and at opposite sides of the clamping members for releasing the clamping action upon the occurrence of excessive longitudinal tension upon the cable at either side of the suspension means. 55
19. In combination with cable suspension means mounted for swinging movement, a support pivoted thereto, upper and lower cable clamping members located within said support, a pivotal mounting for connecting the lower clamping member with the support at a point below the cable, means normally maintaining said clamping members in clamping relation to the cable, and upwardly extending means mounted at said pivotal mounting and coacting with the upper clamping member for releasing the clamping engagement upon the occurrence of an excessive longitudinal strain upon the cable at one side of the support. 60

In testimony that I claim the foregoing as my invention, I have signed my name hereto.

ARTHUR WILLIAM GOTHLBERG.
